TRIPPING DEVICE

Jacob W. Ogden, Springdale, Conn., assignor to
 Pitney-Bowes Postage Meter Co., Stamford,
 Conn., a corporation of Delaware

Application November 24, 1936, Serial No. 112,464

15 Claims. (Cl. 101—235)

This invention relates to a mechanical tripping device which is particularly adapted for use with a machine for controlling the printing of impressions upon articles which are conveyed or otherwise moved to a printing position at high speed, such as for example, the printing of a cancellation mark or a stamp impression upon letters in a mailing machine, which are fed to a printing position by means of continuously driven feed 10 rollers.

In printing cancelling impressions upon letters, it is desirable to have the said impressions come within a predetermined distance from the edge of the letter and since the trip is controlled by each individual letter, it is necessary to start a tripping operation before the leading edge of the letter reaches the printing member.

In other machines of like character, a single tripping point is provided which is brought as near to the printing position as possible to permit the instant operation of the printing member when the trip is engaged by a letter. In the device of this invention, two tripping points are provided, one a comparatively delicate trip, which 25 is actuated by a letter to set a driven element in motion, and a second tripping point which is actuated by the driven element, and which trips the printing member after the letter has advanced from the initial tripping point into proximity with the printing member.

This offers a considerable advantage in that the first tripping point requires very little actuating force, while the second trip, which is driven, has adequate force to produce the result desired. 35 Further, the leading edge of the printing die may be brought close to the impression roller for assuring the accurate placement of the stamp impressions, and it permits the use of an inexpensive friction clutch instead of the more expensive 40 types of clutches.

One object of the invention therefore, is to provide means whereby a mechanical tripping device may be set in motion by the engagement of an article therewith, as the article is fed therestrap 45 to a printing position, and to include means whereby the actual tripping of the printing member is delayed until the article has advanced to the printing position.

Another object is to provide a two point mechanical trip, the first point of which may be actuated by a comparatively delicate force, and the second point of which may be actuated by a greater or driving force which is set in motion by the first force.

55 Another object is to provide a tripping means

which is controlled by the movement of the article through continuous contact therewith.

With the foregoing and other objects in view, which will appear as the description proceeds, the invention resides in the combination and arrangement of parts and in the details of construction hereinafter described and claimed, it being understood that various changes in the precise embodiment of the invention herein disclosed may be made within the scope of what is claimed 10 without departing from the spirit of the invention.

A preferred embodiment of the invention is illustrated in the accompanying drawings, wherein:

Fig. 1 is a plan view with part in section showing article feeding mechanism, a trip mechanism and printing mechanism;

Fig. 2 is a fragmentary plan view showing the position of the tripping mechanism after an article has effected the initial tripping movement of the tripping member;

Fig. 3 is also a fragmentary plan view showing the tripping member in an advanced position and at the point of tripping or releasing the stop from the printing member;

Fig. 4 is a further fragmentary plan view showing the position of the tripping member at the completion of its movement;

Fig. 5 is an end view taken substantially in the direction of the arrows 5—5 of Fig. 1; and

Fig. 6 is an end view looking in the direction of arrow 6 on Fig. 1.

Referring to Fig. 1 the articles to be printed, such as the letter indicated at L, are fed between continuously driven feed rollers 11 past a tripping member indicated generally at 12 and between a printing member 13 and impression roller 14. The printing member is provided with a cancellation die face 15 and a postmark die face 16. It will be noted that the leading end of the cancelling die 15 or the end indicated at 15a is in close proximity with the point of engagement with the impression roller 14 and that the tripping member 12 is spaced at a considerable distance away from the printing member.

The printing member 13 is loosely mounted on a continuously driven shaft 17 and is adapted to be driven by means of a friction clutch member 18, which has one member 18a, (Fig. 6) fixed to said shaft 17. The said printing member is normally held in a non-rotating position by means of a stop arm 19, which forms one arm of a bell crank lever 20. Another arm 19a of said bell crank is connected by means of a link 22 to one

arm 23a of another bell crank lever 23. A spring 24 connected to arm 23b of said bell crank 23, tends to urge the bell crank 23 about its pivot in a counter-clockwise direction to thereby cause the arm 19a of the bell crank 20 to rest against a stop pin 25 and thereby fix the position of the stop arm 19 in the path of the lug 21 on the printing member 13. The bell cranks 20 and 23 are mounted on suitable studs extending from 10 a support plate 28 carried by the machine frame.

The tripping member 12 comprises a disc 26 which is rotatably mounted upon a stub shaft 27, extending below the support plate 28, and rests upon a collar 31, which collar also forms 15 a part of the tripping member as will be later described. The collar rests upon a flange 29 provided at the lower end of the stub shaft 27.

Also secured to the disc 26 is a support block 32 on which is slidably mounted a trip finger 33, 20 which finger is normally urged in a projected position by means of a spring 34, to normally maintain the trip end thereof in the path of the articles. The spring 34 is stretched between an anchor pin 56 secured in said block 32 and a pin 25 57 in the trip finger, there being an elongated slot 55 in the trip finger 33 through which the anchor pin 56 passes.

One edge of the disc 26 is flattened as indicated at 35 with the said flat lying in a plane 30 parallel and adjacent to the path of travel of the article. Opposite said disc 26 and cooperating therewith is a driven feed roller 36.

An article upon being fed by means of the feed rollers 11, will be moved into engagement with 35 the trip finger 33 as shown in Fig. 1, whereupon the disc 26 will be rotated by the engagement of the leading end of the article therewith until the knurled peripheral surface of the disc moves into engagement with the lower surface of the article. 40 From this point the article becomes the driving member through the cooperation of the feed roller 36, the pressure of which roller will force the article against the peripheral surface of the disc 26 and cause the disc to be driven so long as the peripheral edge remains in contact with the article.

During the movement of the disc 26, a pin or 50 striker member 38, which projects upwardly from the top surface of the disc, will be moved into engagement with the arm 23a of the bell crank 23. The bell crank 23 will thus be rocked in a clockwise direction against the pull of the spring 24 to thereby rock the bell crank 20 and remove the stop 19 from its engagement with the lug 21 55 of the printing member. The trip pin 38 will continue to move past the arm 39 during the rotation of the disc 26 to thereby permit the bell crank 20 to be reset to its normal position, with the stop arm 19 in the path of the lug 21 for the 60 purpose of stopping the printing die after one revolution of movement.

After the peripheral surface of the disc 26 leaves the lower surface of the article, as shown in full lines, Fig. 4, the said disc 26 will be carried to the end of its revolution by momentum.

The tripping member 12 is stopped after one revolution by means of a structure which will be later described and is latched in its home position by means of a pawl 41 which pawl has one hooked 70 end 42 normally positioned in the path of a lug 43 on the collar 31. The said pawl 41 is pivotally mounted upon a stud 44 and the hooked end 42 thereof is urged toward its stop position by means of a spring 45.

75 When the next article engages the trip finger

33 to start another revolution of the disc 26, the hooked end 42 of the stop pawl 41 will not be removed from its engagement with the lug 43 until after the disc actually begins to move. To accomplish this, the disc 26 is adapted to be 5 moved independently of the collar 31, due to the provision of a lost motion connection which includes a slot 46 in the disc and a pin 47 in the collar 31, which pin projects through said slot and which is maintained in a position against 10 the forward edge of the slot as shown in Fig. 2 by means of a spring 48. Upon the initial movement of the disc 26, as from the position of Fig. 1 to that of Fig. 2, the collar will remain in its fixed position until a pin 49, projecting downwardly from the disc 26, engages a shoulder 51 15 on the pawl 41 and cams the pawl outward from its latched engagement with the lug 43. From the two positions shown in Fig. 2, it will be seen that the camming out of the hooked end 42 of 20 the pawl 41 is accomplished during the period that the lost motion through the slot 46 is taken up.

Immediately after the release of the hooked end 42 from its engagement with the lug 43, the 25 spring 48 will return the collar 31 to its normal relation with the disc 26 to permit both the collar and the disc to rotate together during the remainder of the revolution. Upon the passing of the pin 49 over the shoulder 51 of the pawl 30 41, the said pawl will be returned to its stop position by means of the spring 48 before the disc 26 has completed its revolution.

The trip member 12 is limited to one revolution of movement by the engagement of the tail end 35 of the tripping finger 33 with a fixed stop pin 54 which projects below the support plate 28. A lug 52, provided on the tail end of the trip finger, is adapted to engage a fixed cam 53, which also projects below the plate 28, and by its engagement therewith, will retract the said tail end of the trip finger to a position outside the peripheral surface of the disc 26, where the lug 52 will engage the said stop pin 54 as shown in the broken line position of Fig. 4. After the stopping 45 of the trip member 12, the trip finger 33 will be returned to its normal tripping position by means of the spring 34. The parts will thus have returned to their normal positions as shown in Fig. 1, and they will remain in this position until 50 the next article engages the trip finger 33.

From the foregoing, it will be seen that a simple and improved mechanical tripping device has been provided which is adapted to be set in motion by a most delicate force, which force is the 55 means for preparing the device for connection with a more substantial driving force to perform the final tripping operation.

What is claimed is:

1. In a device for printing upon moving articles, the combination with a driven rotary printing member having stop means to normally prevent the rotation of said printing member; of trip mechanism associated with said stop means including a primary trip member having a normally stationary position and movable upon the engagement of a moving article therewith, and a secondary trip member movable with said primary trip member and arranged to release the stop after the primary trip has moved through 70 part of its cycle.

2. In a device for marking moving articles, a rotary printing member including a drive therefor, a stop normally holding the printing member in a non-driving relation with the drive, a trip 75

member normally at rest arranged to be engaged by the leading end of a moving article and to be moved by said engagement to a driven position, and means arranged in a fixed position relative to the trip member and adapted to effect the release of the stop member after said trip member is moved to a driven position.

3. In a device for printing upon moving articles, a printing member, stop means to hold said printing member in a non-printing position, a rotatable tripping device engageable by an article in advance of the printing position, a trip pin movable upon engagement of an article with said tripping device, and a stop releasing member positioned in the path of said trip pin and in a spaced relation thereto, whereby the actual release of the printing member is delayed until the article has passed from the tripping device to a printing position.

20 4. In a device for marking moving articles, a rotary printing member including a drive therefor, a stop normally holding the printing member in a non-driving relation with the drive, a driven feed roller adapted to engage and advance each 25 article, a rotatable member associated with said feed roller but normally arranged in non-driving relation therewith, means projecting from said rotatable member into the path of the moving articles and adapted to cause sufficient rotation of 30 said rotatable member upon engagement of an article therewith to move the rotatable member into driving relation with the moving article, and means on said rotatable member to trip the stop and thereby effect a printing operation.

35 5. In a device for printing upon moving articles, the combination with a driven rotary printing member having stop means to normally prevent the rotation of said printing member; of a trip to release said stop including a rotatable 40 member having a portion thereof projecting in the path of the moving articles, whereby upon engagement of the leading edge of an article therewith the rotatable member is given a partial rotation and the periphery thereof moves into 45 engagement with one surface of the article; a driven feed roller engaging the opposite surface of the article and cooperating to continue the rotation of the rotatable member after the article passes said projecting portion, stop releasing 50 means, and a striker member movable with said rotatable member and arranged to engage the stop means to release the printing member and effect a printing operation after the rotatable member has been moved by the article.

55 6. In a device for printing upon moving articles, the combination with a driven rotary printing member having stop means to normally prevent the rotation of said printing member; of a trip mechanism associated with said stop means 60 including a rotatable member which is adapted to be driven by its peripheral engagement with one surface of the article, and a striker member movable with said rotatable member and arranged to engage said stop to release the printing member and effect a printing operation after the leading end of an article has passed beyond the rotatable member.

7. In a device for printing upon moving articles, a printing member, a stop normally retaining the printing member in a non-operative position, means to release said stop including a rotatable member, a yieldable finger mounted upon said rotatable member and projecting into the path of the moving articles to provide partial 75 rotation to the rotatable member when engaged

by an article, a driven feed roller cooperating with the rotatable member and effective to continue the rotation of the rotatable member through the driving engagement of the feed roller with the article, and a stop tripping member carried by 5 said rotatable member arranged to release the stop after the rotatable member has been partially rotated and thereby effect a printing operation.

8. In a device for printing upon moving articles, the combination with a driven printing member having stop means to normally prevent the movement thereof, of a tripping device normally arranged in a rest position, means whereby said tripping device may be moved when engaged 10 by an article, a trip member on said tripping device positioned so as to release the stop means after the tripping device has been moved a pre-determined distance and to thereby effect the tripping of the printing member and means to 15 limit the rotation of the tripping device to one revolution.

9. In a device of the class described, the combination with article feeding means, a rotary printing member, a drive for said printing member, 25 and a stop to normally retain the printing member in a non-driving relation with the drive; of means to trip said stop, including a rotatable member normally arranged in a rest position, a driven feed roller associated with said rotatable 30 member and adapted to move the articles therepast, said rotatable member and feed roller being arranged at either side of the path of travel of the articles, means projecting into the path of an article to rock the rotatable member into 35 a position where it may be driven by frictional contact with the moving article, and a striker member carried by said rotatable member arranged to release said stop and effect a printing 40 operation when the article has advanced to a printing position.

10. In a device of the class described, the combination with article feeding means, a rotary printing member, a drive for said printing means, and a stop to normally retain the printing member in a non-driving relation with the drive; of a rotatable disc member normally arranged in a rest position and having one flat edge lying adjacent and parallel to the path of travel of the articles, a driven feed roller associated with 50 said disc member and arranged opposite said flat, a projection on said disc projecting into the path of an article and adapted to be engaged by an article to rock the disc member into a position where its periphery will move into frictional contact with the article, and a striker member carried by said disc arranged to release said stop and effect a printing operation when the article has advanced to a printing position. 55

11. In a machine of the class described wherein articles are fed to a rotatable printing member; stop means to normally retain the printing member in a rest position, tripping means including a disc member having one flat edge lying 60 adjacent and parallel to the path of travel of the articles, a yieldable member projecting above the flat surface and into the path of the moving articles to provide partial rotation to the rotatable member when engaged by an article and thereby move the periphery of the disc into frictional driving engagement with the article, means on said disc to trip the stop means during the rotation of the disc and thereby effect a printing operation, and an abutment member positioned 65 70 75

in the path of the yieldable member to limit the rotation of the disc to one revolution.

12. In a machine of the class described where-
5 in articles are fed to a rotary printing member,
stop means to normally retain the printing mem-
ber in a rest position, tripping means including
a disc member having one flat edge lying ad-
jacent and parallel to the path of travel of the
articles, a yieldable member projecting above the
10 flat surface into the path of the moving articles
to be engaged by said articles and thereby rock
the disc to move the peripheral surface of the
disc into engagement with the article and be
rotated thereby, means on said disc to trip the
15 stop means during the rotation of the disc, a
disc stopping member, means to project one end
of said yieldable member beyond the periphery
of the disc and into the path of said disc stop-
ping member to limit the rotation of the disc to
20 one revolution, and means to retract said yield-
able member into the path of the moving articles
at the end of the revolution.
13. In a tripping device operable to release a
normally inactive printing member by the en-
gagement of moving articles with said device
25 and comprising: one trip member extending into
the path of the articles and movable by the
limited force of an article, and a second trip
member movable by the action of the first trip
30 member into frictional driving engagement with
one surface of a moving article, and a striker
member on the second trip member arranged to
trip the printing member.

14. In a device for tripping a normally in-
active printing member comprising in combina-
tion: letter feeding means including a feed
roller; a letter actuated trip including a rotatable
member positioned opposite said feed roller and 5
having a trip finger extending into the path of
the moving letters, which, when engaged by a
letter, is adapted to rock the periphery of the
rotatable trip member into driving engagement
with one surface of the moving letter; a second 10
trip member associated with the driven rotatable
member, and means associated with the printing
member arranged in the path of said second trip
member so as to be engaged thereby to effect the
release of the printing member.

15. A trip actuating device, comprising a ro-
tatable member, means to normally latch said
member in a stationary position, means carried
by said member and normally projecting into
the path of moving articles adapted to provide 20
partial rotation to the member while a moving
article is engaged with said projection, means to
permit partial movement of the rotatable mem-
ber while the latch means remains latched, means
to release said latch after an initial movement of 25
the rotatable member, a device to be tripped
having a projecting member associated therewith,
and a trip engaging means movable with said
rotatable member and arranged to engage said
projecting member to effect a tripping operation 30
during the rotation of the movable member.

JACOB W. OGDEN.
